A. E. CRAMER,
CARD GAME,
APPLICATION FILED MAY 26, 1917.

1,263,860.

Patented Apr. 23, 1918.

2 SHEETS—SHEET 1.

FIG. 1.

FIG. 6.

FIG. 2.

FIG. 7.

FIG. 3.

FIG. 8.

FIG. 4.

FIG. 9.

FIG. 5.

FIG. 10.

FIG. 11.

WITNESSES

INVENTOR

Arthur E. Cramer

W. E. Fielding.
Lloyd W. Batch

BY

Richard Oliver.

ATTORNEY

A. E. CRAMER.

CARD GAME.

APPLICATION FILED MAY 26, 1917.

1,263,860.

Patented Apr. 23, 1918.

2 SHEETS—SHEET 2.

FIG. 12.

1^a

FIG. 13.

9^a

FIG. 14.

1^b

Hay $.50 Per Ton

Corn $.75 Per Bus.

Oats $.50 Per Bus.

FIG. 15.

1^a

FIG. 16.

9^a

FIG. 17.

9^b

FIG. 18.

7^a

Barley $1.00 Per Bus.

Wheat $.150 Per Bus.

Hog $.50

FIG. 19.

Sheep $.15.

FIG. 20.

Calf $.10.

FIG. 21.

Cow $.60.

1^a

6^a

10^a

FIG. 22.

1^b

7^b

9^b

11^b

Rain on Hay

Frosted Corn

Rusted Oats

Blighted Barley

5^b

8^b

9^b

7^b

Wheat Hail

Tornado

Hog Cholera

Steer Bloat

9^b

9^b

10^b

13^b

Sheep Scab

Calf Bloat

Cow Tuberculosis

Hoof and Mouth Disease

INVENTOR

WITNESSES

W. C. Fielding
Lloyd W. Patch

BY

Richard Oliver.

ATTORNEY

UNITED STATES PATENT OFFICE.

ARTHUR E. CRAMER, OF BELGRADE, MONTANA.

CARD GAME.

1,263,860.

Specification of Letters Patent. Patented Apr. 23, 1918.

Application filed May 26, 1917. Serial No. 171,273.

To all whom it may concern:

Be it known that I, ARTHUR E. CRAMER, a citizen of the United States, residing at Belgrade, in the county of Gallatin and State 5 of Montana, have invented certain new and useful Improvements in Card Games, of which the following is a specification.

This invention relates to an improvement in card games and more particularly to a 10 game apparatus which can be used by two or several persons competing single handedly, one against the other, or paired off and playing as partners, it being a purpose of my invention to provide a game apparatus 15 and rules for the use of the same in play which will make the card game one which will prove interesting to old or young, and which can be played without any special skill or knowledge on the part of the individual players.

A further object lies in providing a game 20 which will be educational for children or young persons as it teaches something of the prices of various farm products as well as 25 the way in which they are sold and handled, and also instructs in the use of figures through constant drill in the using of the same in the playing of the game; the successful playing also acting to quicken the 30 perception, to cultivate close observation, and to develop the power of concentration.

With the above and other objects in view 35 which will be in part described and in part understood from the specification, drawings and claims, my invention consists in certain novel features of construction, and combinations of parts which will be hereinafter more fully set forth.

In the drawings:—

40 Figures 1, 2, 3, 4, 5, 6, 7, 8, 9, and 10 show specimen cards of various groups used to make up a playing deck;

Fig. 11, within the bracket, shows specimen 45 of the purchase or buying checks;

Figs. 12, 13, 14, 15, 16, 17, 18, 19, 20, and 50 21, illustrate specimen cards of various groups making up a price deck; and

Fig. 22, within the bracket, shows a set 55 of bad luck or forfeit cards which are to be included with the various groups of cards embraced in the price deck.

It is perhaps preferable that the cards of the playing deck and those of the price deck be made of relatively different size or shape, and perhaps of distinctive color, so that the 55 cards of the two decks can be readily distinguished when laid upon the table or in shuffling or dealing, and as the forfeit cards are to be contained in the price deck, these cards will be of the same size and preferably 60 on the same stock as the cards of the price deck. As an instance, the cards of the playing deck might be made larger than those of the price deck and could be of white card stock, whereas the cards of the smaller or 65 price deck, and including the forfeit cards could be made of blue stock.

The playing deck comprises ten respective groups each numbering twelve cards, and a consequent total of one hundred twenty 70 cards in all, a specimen card of each of the groups being indicated by the reference characters 1, 2, 3, 4, 5, 6, 7, 8, 9, and 10, where these cards are shown in Figs. 1 to 10 inclusive of the drawings. The cards of 75 the various sets are marked "Hay—Tons", "Corn—Bushels", "Oats—Bushels", "Barley—Bushels", "Wheat—Bushels", "Hog", "Steer", "Sheep", "Calf", and "Cow", it being understood that there will be twelve 80 cards in each group and that the same designation will be placed upon each of the cards, the cards with the crop products, however having units of measure for the various products as presented stated thereon, and 85 then having numbers to represent quantities of the respective units of measure, for instance, the "Hay" cards would be marked from 1 to 12 tons, the "Corn", "Barley", "Oats" and "Wheat" cards would run from 90 10 to 120 bushels, that is 10, 20, 30, 40, 50, 60, 70, 80, 90, 100, 110, 120 bushels.

The price deck is made up of various groups which pair off with the groups of cards as provided in the playing deck, the 95 card group 1^a of the price deck pairing with the group 1 of the playing deck, group 2^a pairing with the group 2, etc., on through group 10^a, which pairs with group 10, the cards of the various groups 1^a to 10^a respectively being marked to indicate various prices by the units of measure for the crop products and various prices per head for the live stock, these cards ranging as follows as the number of cards in each set and the price indication thereon:

“Hay”, 4 cards; $5, $10, $15, $20, per ton.

“Corn”, 4 cards; $.25, $.50, $.75, and $1 per 5 bu.

“Oats”, 4 cards; $.25, $.50, $.75, and $1 per bu.

“Barley”, 4 cards; $.25, $.50, $.75, and $1 per bu.

10 “Wheat”, 4 cards; $.50, $.75, $1 and $1.50 per bu.

“Hog”, 5 cards; $5, $10, $15, $20, and $25.

“Steer”, 5 cards; $80, $90, $100, $110, and $120.

15 “Sheep”, 5 cards; $5, $10, $15, $20, and $25.

“Calf”, 5 cards; $5, $10, $15, $20, and $25.

“Cow”, 5 cards; $60, $70, $80, $90, and $100.

20 In addition to the aforementioned cards, the forfeit cards of the group as illustrated in Fig. 22 are included with the price deck and those forfeit cards are intended to pair off with sets or groups of cards of the price 25 deck and the corresponding groups of the playing deck, so that the card 1^b which pairs with the card of the group 1 and 1^a reads “Rain on hay”; the card 2^b pairing with the groups 2 and 2^a reads “Frosted corn”; the 30 card 3^b pairs with groups 3 and 3^a, reads “Rusted oats”; card 4^b, reading “Blighted barley” is to be paired with groups 4 and 4^a; forfeit card 5^b is paired with groups 5 and 5^a; and reads “Wheat hailed”; the card 35 reading “Hog cholera” and designated 6^b is to pair with the cards of the groups 6 and 6^a; the card designated 7^b and which reads “Steer bloat” pairs with cards of the groups 7 and 7^a; those cards in the groups 8 and 8^a 40 are to be paired with the card 8^b which is marked “Sheep scab”; the card marked “Calf bloat” and designated as 9^b, pairs with the groups 9 and 9^a; and card 10^b of the bad luck or forfeit group, and which is marked 45 “Cow tuberculosis” is to be paired with the groups 10 and 10^a respectively. The ten specific designations are so proportioned that five stock products are specified on the one hand while five animals of farm live stock 50 are designated in the remaining groups, and in the forfeit group of cards there are included two extra cards, X and Y which are marked “Tornado” and “Hoof and mouth disease”, respectively, these cards referring 55 in a manner to be hereinafter more fully set forth to the two general classifications of groupings, namely the stock products and the live stock. It will be seen that all in all the price deck with the forfeit group included therein comprises a total of fifty seven cards. While it has been stated that ten groups are made, and a certain specific 60 number of cards for each group, it will of course be understood that twelve groups of ten cards each might be embraced in the 65 playing deck and a total of one hundred and twenty cards yet maintained, or that the number of groupings and the number of cards in each group could be varied without limitation or without reference 70 to the total number of cards which might be embraced in the complete set, the present adaptation being one which in practice has proven to provide a number of cards conveniently handled and which will permit 75 the entrance of several persons into the playing of the game. As the price cards and the forfeit cards bear substantially immediately upon the various groupings in the playing deck, the number of classifications and the 80 number of cards in each classification will in a measure be governed and controlled by the character of the cards constituting the playing deck, however, it will be of course understood that a greater or lesser number 85 of price cards might be included in each particular classification or grouping and that the game might thus be made more or less complicated.

As in the playing of the game there is to 90 be bartering back and forth between the players, purchase checks Z, several of which are illustrated in Fig. 11 are provided. For ordinary purposes it will be found that checks aggregating a value of say $4,000 95 and in denominations representing $20, $10, $5, and $1, are convenient and sufficient for the purpose desired, however, under some circumstances it might be found desirable to provide purchase checks of the denomination representing $50, $100, and the like, and a greater or lesser number of the checks might be provided which would thus represent a greater or lesser aggregate value.

It will be understood that the various 105 cards might be made up of any suitable stock and might be made rectangular as here shown, rounded at the corners or shaped in any other suitable and desired manner, and in addition to having the various group 110 markings thereon, the cards might have printed on their faces, pictorial representations to thus show at a glance, and without the necessity of reading the printed matter, to just which group the respective cards are 115 assigned. This same marking by the pictorial representation might be carried through the playing deck and the general forfeit cards “Tornado,” and “Hoof and mouth disease,” indicated by the reference 120 characters X and Y, might have any desired pictorial representation placed on the faces thereof. The purchase checks Z might be of card board, celluloid, composition of materials, or of any other desired and suitable 125 material and the money valuations might be printed, stamped, or molded thereon.

Rules for playing.

The game may be played by two or more 130 persons, say up to eight and the players may stand individually or may be paired and act as partners.

At commencement of play each player 5 takes or is given, purchase checks or chips of an aggregate amount equal to the sum total of the checks taken by the remaining players, say checks representing a value of $500. The player who is to act as dealer 10 takes both decks and after thoroughly shuffling and mixing the cards of the decks separately deals the cards from the playing deck one at a time and face up on the table, around the table until each player has five 15 cards, the small or price deck is then taken and with the cards of the forfeit group shuffled therein is dealt so that one card passes to each player face down.

Play may now begin and each player will 20 proceed to dicker with his neighbor to buy or sell according to his or their price cards, giving in barter the required amount in purchase checks. For instance, if a player having the price card marked "Steer-$100," 25 can buy a steer from his neighbor for purchase checks aggregating a total of $70, he can then figure that on this deal he has made $30, as the value of a steer in accordance with the price card held in his hand is 30 $100. As soon as any one player shall have purchased or otherwise obtained four of the cards of any one particular group of the playing deck, he shall be considered as having "a carload," and these four cards with 35 the corresponding price cards placed on top thereof will be laid to one side. In the case of "a carload" of steers having been acquired or in the case that one player corrals four of the cards of the "Steer" group, and 40 holds one of the price cards marked "Steer-$100," then he shall be considered as having purchased or acquired "steers" to the value of $400. It is however to be understood that only one "carload" can be purchased for 45 each individual price card.

When the players have finished their dickering for the purchase of cards of the playing deck the dealing is continued by giving each player one card from the playing deck 50 and then a further period of dickering and bartering is indulged in. Upon further cessation of trading, still additional cards will be dealt from the playing deck. Each player can call for a price card whenever he 55 wishes or whenever occasion requires, but is not compelled to take additional cards from the price deck simply because additional cards are taken by other players. When additional cards are taken from the 60 price deck, if one of the cards from the forfeit group be drawn, as for instance "Frosted corn," then the player drawing this card must surrender back to the dealer all of these cards of the corresponding group of the 65 play and price decks which he may have in his hand or on display before him upon the table, these cards being immediately reshuffled into their respective decks. If perchance the forfeit card marked "Tornado" be drawn by any player, this will mean that 70 all of the cards of both decks must be forfeited back and surrendered to the dealer, or if the card "Hoof and mouth disease," shall be drawn, then all of the cards of the various live stock groups must be surrendered. 75

Dealing ceases when the dealer runs out of the cards of the playing deck, and then all cards of this deck which are subsequently surrendered through the players drawing the 80 forfeit cards shall be laid to one side and considered as dead. Play shall cease when all of the cards have been dealt from the playing deck and when the players shall have finished dickering and bartering, and 85 this shall be considered the end of the game.

Scoring.

Whenever a player puts to one side a "carload" or four cards of one of the groups of 90 the playing deck, with a corresponding price card from the price deck, these cards shall be considered dead until the final count, and the drawing of one of the forfeit cards shall not act to compel the surrender of the cards 95 thus laid aside. In settling up the final count to determine the winner of the game, each player shall figure up the respective and total value of the "carload" which he may have corralled during play, giving a 100 valuation to the items of the carload corresponding to the price valuation on the price card grouped therewith; the total valuation of the purchase checks as still retained by each player is then determined and this is 105 taken with the total valuation of the "carloads" acquired during play as the net winnings of the player.

The party or player having the greatest sum total to his credit shall be considered as 110 the winner.

From the foregoing it will be seen that I have provided a card game apparatus which is of such character that by following the rules as set down, or other rules which might 115 be devised, the game may be played by young or old without special previous knowledge, and that when the game is played by young it is educational and instructive to a high degree and while I have herein shown and 120 described only certain groupings of the cards of the various sets or decks and have set forth only one set of playing rules, it will be understood that changes and variations might be resorted to in the number of 125 groups and the number of cards in each group of the various decks, and the playing rules might be revised, and that other changes and variations might be resorted to without departing from the spirit and scope 130 of my invention, and hence I wish to be limited only to such points as may be set forth in the claims.

I claim:

- 5 1. A card game including a deck of cards having cards therein marked to designate various farm products, a second deck of cards having thereon designations of the first mentioned deck and also supplied with 60 price markings, and forfeit cards included in the second mentioned deck representing disaster which may befall the farm products named in the various designations of the first mentioned deck.
- 10 2. A card game including a deck of cards having cards therein marked to designate various farm products, a second deck of cards having thereon designations of the first mentioned deck and also supplied with 65 price markings, forfeit cards included in the second mentioned deck representing disaster which may befall the farm products named in the various designations of the first mentioned deck, and purchase checks to be used in barter for the various cards of the first mentioned deck.
- 15 3. A card game including a deck of cards having cards therein marked to designate various farm products, a second deck of cards having thereon designations conforming to those of the first mentioned deck and supplied with price markings, and purchase checks to be used in barter for the various 70 cards of the first mentioned deck.
- 20 4. A card game including a deck consisting of a plurality of groups some of which cards have pictorial representations thereon to designate a particular farm product and also an inscription to name the farm product, a 75 second deck of cards of a character distinctive from the first mentioned deck which cards also have pictorial representations and designating markings and further have price markings thereon, and a forfeit card 80 for each of the various groupings of the first mentioned deck being marked with some disaster which might befall the farm product named in the various groups of said first mentioned deck the forfeit cards being included with the cards of the second deck.
- 25 5. A card game including a deck consisting of a plurality of groups each of which has a pictorial representation thereon to designate a particular farm product and also 85 an inscription to name the farm product, a second deck of cards of a character distinctive from the first mentioned deck which cards are also supplied with pictorial representation and the designating marking and further have price markings thereon, a forfeit card for each of the various groupings of the first mentioned deck marked with some disaster which might befall the farm product named in the various groups of said first mentioned deck the forfeit cards being 90 included with the cards of the second deck, and purchase checks to be used in barter for the various cards of the first mentioned deck.

6. A card game including a deck of cards having therein cards marked to designate 70 various farm products which cards are separated into two groups on the one hand representing crop products and on the other live stock, a second deck of cards having 75 designations of the first mentioned deck and also supplied with price markings, and group forfeit cards included in said second mentioned deck and marked thereon to name a disaster which may befall the crop products and the live stock.

7. A card game including a deck of cards having therein cards marked to designate various farm products which cards are separated into two groups on the one hand representing crop products and on the other 80 live stock, a second deck of cards having designations of the first mentioned deck and also supplied with price markings, group forfeit cards included in the second mentioned deck and marked thereon to name a 85 disaster which may befall the crop products and the live stock, and other forfeit cards marked with designation of disaster which might befall the individual farm products as named in the first deck.

8. A card game including a deck of cards having therein cards marked to designate various farm products which cards are separated into two groups on the one hand representing crop products and on the other 90 live stock, a second deck of cards having designations of the first mentioned deck and also supplied with price markings, group forfeit cards included in the second mentioned deck and marked thereon to name a 95 disaster which may befall the crop products and the live stock, other forfeit cards marked with designation of disaster which might befall the individual farm products as named in the first deck, and purchase 100 checks to be used in barter for the various cards of the first mentioned deck.

In testimony whereof I affix my signature in presence of two witnesses.

ARTHUR E. CRAMER.

Witnesses:

ALFORD YERGEY,
JOHN W. YERGEY.